UNITED STATES PATENT OFFICE.

EDWIN DOW TUCKER, OF SANTA BARBARA, CALIFORNIA.

PUNCH.

No. 813,843.

Specification of Letters Patent.

Patented Feb. 27, 1906.

Application filed May 23, 1905. Serial No. 261,837.

To all whom it may concern:

Be it known that I, EDWIN Dow TUCKER, a citizen of the United States, residing at Santa Barbara, in the county of Santa Barbara and State of California, have invented new and useful Improvements in Punches, of which the following is a specification.

My invention relates to a punch for providing an air-vent and an outlet-opening in the top of a hermetically-sealed receptacle, whereby the contents thereof may be freely withdrawn.

One object of the invention is to provide means for resiliently supporting the punch in applied position, whereby a slight pressure upon the punch will provide the necessary openings, and whereby the punch may be elevated to remove the points thereof from the openings to permit the withdrawal of the contents of a receptacle and to be replaced and held within said openings to again seal the receptacle.

A further object of the invention is to provide means to prevent the punch from penetrating the top of the receptacle when pressure is accidentally brought to bear thereupon.

A still further object of the invention is to provide the punch with means which will assist the points thereof in preventing the admission of air to the receptacle after the air-vent and outlet-opening have been provided, and the points of the punch are again seated therein.

The invention consists in the construction, combination, and arrangement of parts hereinafter fully described, claimed, and illustrated in the accompanying drawings, which disclose the preferred form of my invention, and in which

Figure 1 is a top plan view of a receptacle provided with a punch constructed in accordance with my invention. Fig. 2 is a central longitudinal sectional view of the upper portion of said receptacle, and Fig. 3 is a similar view illustrating the manner in which the punch penetrates the top of the receptacle.

Referring to the drawings by reference-numerals, 1 designates the upper portion of a receptacle, such as are provided for the preservation of cream, milk, and the like, and 2 the top thereof, which is of the usual construction and which is hermetically sealed in applied position. The top 2 is provided at di-

ametrically opposite points with two indentations 3.

The punch consists of an elongated body 4, having two downwardly-projecting penetrating-points 5, which are adapted to be received by the indentations 3. A spring-retaining member 6 has one end secured to the top 2 and has movably secured to its other end the punch 4. The member 6 serves to horizontally retain the punch in applied position upon a receptacle, so as to prevent the loss of the punch and to retain the closure down upon the top of the receptacle to prevent its forming an obstruction. The member also permits the punch to be elevated to remove its points from the openings made thereby and turned to one side to clear the openings, and it permits the points of the punch to be again inserted into the openings and serves to force the punch and hold the same down upon the top of the receptacle to seal the openings. These indentations are provided for the reception of the points 5 in order that the device may lie as closely to the top 2 as is possible, whereby the device is prevented from forming an obstruction when one receptacle is placed upon another, as is common when packing such receptacles for shipment.

In order to prevent the points 5 from accidentally penetrating the bottoms of the indentations 3, I interpose washers 7, of any suitable material, between the top 2 and the under side of the punch 4. When it is desired to cause the points 5 to penetrate the bottoms of the indentations 3, said washers 7 are first removed and then pressure is brought to bear upon the punch 4. After the necessary openings have been provided the points 5 are extracted and then the punch 4 is turned into the position illustrated in Fig. 1 of the drawings, thus permitting the contents of the receptacle to be withdrawn. If it is desired to use only a portion of the contents of the receptacle, the points 5 of the punch 4 are again seated in the openings to seal the same. The end of the spring member 6 projects beyond the punch 4, whereby to provide a handle by means of which the points of the punch may be placed within or extracted from the openings.

A strip 8, of any suitable material, is secured to the under side of the punch 4 and about the points 5, whereby said strip closes the openings to securely seal them.

From the foregoing description, taken in connection with the accompanying drawings, the construction and mode of operation of the invention will be understood without a further extended description.

Changes in the form, proportions, and minor details of construction may be made within the scope of the invention without departing from the spirit or sacrificing any of the advantages thereof.

Having thus fully described the invention, what is claimed as new is—

1. In a device of the character described, a receptacle, a spring member having one of its ends rigidly secured to the receptacle, and a punch secured to the free end of said spring member, whereby to permit the punch being withdrawn and replaced in a perforation made in the receptacle thereby.
2. In a device of the character described, a receptacle, a spring member having one of its ends rigidly secured to the receptacle, and a punch movably secured to the free end of said spring member, whereby to permit the punch being removed and replaced in a perforation made in the receptacle thereby.
3. In a device of the character described, a receptacle, a spring member having one of its ends rigidly secured to said receptacle, and a double-pointed punch secured to the free end of said spring member, whereby to permit the punch being withdrawn and replaced in perforations made in the receptacle thereby.
4. In a device of the character described, a receptacle, a spring member having one of its ends rigidly secured to said receptacle, a punch secured to the free end of said spring member, whereby to permit of its being re-

moved and replaced in a perforation made in the receptacle thereby, and a sealing means carried by the punch.

5. In a device of the character described, a receptacle, a spring member having one of its ends rigidly secured to said receptacle, and a punch secured to the free end of said spring member, the end of said spring member projecting beyond the punch to provide a handle by means of which the punch may be removed and replaced in a perforation made in the receptacle thereby.

6. In a device of the character described, a receptacle having the top thereof provided with indentations, a spring-retaining member secured to the top thereof, a punch movably secured to said retaining member and provided with points adapted to normally occupy said indentations, means for preventing said punch from accidentally penetrating the bottoms of said indentations, and a sealing member secured to said punch.

7. In a device of the character described, a receptacle provided with an indentation, a yielding member secured to the receptacle, a punch secured to the yielding member and provided with a point adapted to be seated in said indentation, a seal means carried by the punch, and means carried by the punch for preventing the point thereof from accidentally penetrating the bottom of said indentation.

In testimony whereof I affix my signature in presence of two witnesses.

EDWIN DOW TUCKER.
